FLASH LIGHT

Otto C. Britsch, New York, N. Y., assignor, by
mesne assignments, to Bond Electric Corpora-
tion, Jersey City, N. J., a corporation of Dela-
ware

Application December 10, 1931
Serial No. 580,030

4 Claims. (Cl. 240—10.67)

This invention relates to portable lighting de-
vices and more particularly is directed to pocket
battery flashlights.

Among the objects of the invention is the pro-
vision of an improved device of the character
described comprising few and simple parts which
shall be easily assembled to form a reliable and
dependable lighting means capable of withstand-
ing rough and hard usage yet which shall be
10 small and compact so that it can be readily car-
ried in the pocket or in hand bags, which shall
be neat in appearance, convenient to handle and
operate, cheap to manufacture, and practical and
efficient to a high degree in use.

15 Other objects of this invention will in part be
obvious and in part hereinafter pointed out.

The invention accordingly consists in the fea-
tures of construction, combinations of elements
and arrangements of parts which will be exem-
20 plified in the construction hereinafter described
and of which the scope of application will be
indicated in the following claims.

In the accompanying drawing, in which is
shown one of the various possible illustrative
25 embodiments of this invention.

Figure 1 is a cross sectional view taken through
a pocket flashlight constructed to embody the
invention showing the cover in closed position.

Figure 2 is a fragmentary cross-sectional view
30 taken on line 2—2 of Figure 1.

Figure 3 is a cross-sectional view taken on
lines 3—3 in Figure 1 showing the lamp removed
from the socket, and

Figure 4 is a fragmentary cross-sectional view
35 taken through the cover and switch portions of
the improved socket flashlight showing the cover
in its retained open position.

Referring to the drawing, 10 denotes a pocket
flashlight of a type that can conveniently be
40 carried in a vest pocket or in a woman's hand
bag, constructed to embody the invention. Said
flash-lamp 10 may comprise a suitable outer cas-
ing 11, as here shown being formed of sheet met-
al, enclosing a battery of one or more dry cells
45 12 and 13. Only one of these cells, namely 12,
need be insulated by a wrapper 14 of paper, fibre
or other suitable material, from the other cell
13 and the casing 11, thereby simplifying the
construction. The upper end 11a of the casing
50 extends beyond the carbon and zinc terminals

12a and 13a of the cells 12 and 13 respectively
to provide a housing for a lamp receptacle socket
15 carrying a standard miniature incandescent
bulb 16 and for a switch 17 for making and
breaking the circuit from said battery cells to
55 the bulb 16.

The socket 15 and switch 17 are mounted to
extend down from the under side of an insulat-
ing plate 18 and a suitable cover 19 is movably
mounted to enclose and shield the bulb portion
60 which extends through said plate 18 to the up-
per side thereof. Said plate 18, socket 15, switch
17 and cover 19 form a closure member, desig-
nated generally at M, for the upper end of the
casing 11. Said member M is retained in posi-
65 tion by an inturned flange 11b provided on the
casing end 11a, said flange forming an abut-
ment engaging the peripheral portion of the
plate 18, as is clearly shown in Figures 1, 2 and
4. The socket 15 preferably is made of a single
70 stamping bent to provide spring shell contact
portions 15a for receiving the screw base 16a of
the bulb 16, spaced lugs 15b which are extended
up through the plate 18 for anchoring the socket
15 thereto, and an extending spring contact por-
75 tion 15c which forms part of the switch 17.

The current carrying parts of the flash-lamp
include, besides the shell contact and contact
portions, 15a and 15c, respectively, a blade 17a
80 of the switch 17, said blade terminating the lower
end or foot 20a of a hinge lever 20. The upper
end 20b of said hinge lever 20 is pivoted at 21
to an outer end of an arm 22 which is anchored
to the inside of the cover 19 by any suitable
85 means, such as rivet 23. A helically wound com-
pression spring 24 is provided between said lever
foot 20a and the plate 18, said lever 20 being
positioned to pass through the spring and through
an opening 18a in the plate 18, as is clearly shown
90 in Figures 1, 2 and 4.

The foot 20a also has an extension abutment
stop 25 which is adapted to contact with the
underside of the plate 18 for swinging the blade
17a to contact with the spring contact portion 15c
on moving the cover 19 to its open position shown
95 in Figure 4. Straddling the spring 24 and the
lower end of the lever 20 under the plate 18, there
is provided a saddle jumper 26 which has spring
sides 26a for contacting with the inside surface
of the upper casing 11a and has lower spring
100

contact ends 26b for abutting the zinc battery terminal 13a. The upper end 26c of the saddle jumper 26 may be provided with a lug 26d which extends into the opening 18a for retaining said 5 jumper from being accidentally displaced. The jumper 26 also serves as spacing and bracing means between the battery cell and the plate 18 as well as a current carrying part of the electrical circuit.

10 The bottom end of the casing 11 may be bent to form an inturned flange 11c on which is seated an insulating closure 28 for enclosing the battery, a jumper 29 being provided for electrically interconnecting the carbon terminal 13b of the 15 cell 13 with the zinc terminal 12b of the cell 12 to join the battery cells in series circuit.

The practical operation of the invention will now be apparent. The battery cells 12 and 13 and closure member M are assembled in the cas-

20 ing 11 with the bulb 16 inserted in the socket 15, as shown in Figure 1. The center contact 16b of the bulb base 16a will then tightly contact with the carbon cell terminal 12a. The shell contact portions 15a of the socket 15 are each 25 provided with an impressed thread 15d for engaging the screw base 16a in the well understood manner. When the cover 19 is in closed position, the switch is in open circuit position, as at X.

To operate the flash-lamp 10 for lighting the 30 bulb 16, the cover 19 is swung open on the pivot 21, a lip 19a being provided on the cover 19 to facilitate the opening operation. As the cover 19 swings to its open position, shown in Figure 4, the spring 24 is compressed by the raising of the 35 lever member 20 and the blade 17a is brought into rubbing contact with portion 15c. The stop 25 contacting on the under side of the plate 18 serves as a fulcrum of a leverage for throwing the plate 17a upwardly and toward the socket 40 extension portion 15c. These interconnecting switch and cover hinge parts which operate on opening the cover 19, are disposed to swing the pivotal center 21 to the right of a bearing point Z on the insulating plate 18 so that the cover 45 19 is retained in open position until said center 21 is swung back to the left of the aligning position with respect to said bearing point Z, thereafter the spring 24 acts to automatically swing the cover 19 closed.

50 The circuit from and to the battery cells through the switch 17 and the socket 15 permits the current to first pass from the battery cell zinc terminal 13a to the casing 11 and also to the saddle jumper 26, hence through the spring 55 24 to the lever foot 20a. When the cover 19 is closed, as shown in Figure 1, the circuit is opened at X. Moving the cover 19 to its opening position, raises the blade 17a to contact with the spring extension portion 15c for closing the circuit at Y, as shown in Figure 4. The current then passes successively through the shell contact portions 15a, the lamp 16 and back to the 60 battery cells through the carbon terminal 12a.

The form of the invention disclosed in the 65

drawing contemplates assembling the battery cells and the closure member permanently in the casing 11, the entire device forming a structure of non-demountable parts with the exception of the bulb 16. However, if desired, the 80 casing 11 may be so constructed as to permit the removal and replacement of the battery cells 12 and 13.

It will thus be seen that there is provided a 85 device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawing is to be interpreted as illustrative and not in a limiting sense.

What is claimed is:

1. A flashlight of the character described comprising a metallic casing, a dry cell battery in the casing having one battery terminal in contact with said casing, and a closure member for one end of the casing having an insulating plate, an electric lamp socket mounted to extend between the plate and the battery and adapted to retain an incandescent bulb in contact with the other battery terminal, a cover for removably enclosing said plate and socket, a lever extended 105 through the plate, said lever having an end on one side of the plate hinged to the cover, a compression spring interposed between the other end of the lever and other side of said plate for resiliently attaching the lever and cover to the 110 plate, and a switch actuated by said lever on movement of said cover.

2. In a flashlight of the character described, an end casing closure member comprising an insulating plate having an opening, a lever extending through said opening, a cover pivoted to one end of said lever, and a compression spring interposed between the other end of said lever and said plate.

3. In a flashlight of the character described, 120 an end casing closure member comprising an insulating plate having an opening, a lever extending through said opening, a cover pivoted to one end of said lever, a compression spring interposed between the other end of said lever and said plate, and a current carrying jumper secured by said spring to extend from said plate.

4. In a flashlight of the character described, 125 an end casing closure member comprising an insulating plate having an opening, a lever extending through said opening, a cover pivoted to one end of said lever, a compression spring interposed between the other end of said lever and said plate, a current carrying jumper secured by said spring to extend from said plate, 135 and a switch blade carried by said last mentioned lever end.

OTTO C. BRITSCH.
